DESIGN FOR A BEVERAGE STICK

Joseph Liebschutz, Auburn, N. Y.

Application September 4, 1935, Serial No. 58,434

Term of patent 3½ years

To whom it may concern:

Be it known that I, Joseph Liebschutz, a citizen of the United States, residing at Auburn, in the county of Cayuga and State of New York, have invented a new, original, and ornamental Design for a Beverage Stick, of which the following is a specification, reference being had to the accompanying drawing, forming part thereof.

I claim:—

The ornamental design for a beverage stick, as shown.

JOSEPH LIEBSCHUTZ.
